UNITED STATES PATENT OFFICE.

RICHARD MURR, OF CHICAGO, ILLINOIS.

DESIGN FOR A GLASS BOWL.

No. 39,118.

Specification for Design.

Patented Feb. 11, 1908.

Application filed December 16, 1907. Serial No. 406,786. Term of patent 7 years.

To all whom it may concern:

Be it known that I, RICHARD MURR, a citizen of the United States, residing at Chicago, in the county of Cook and State of Illinois, have invented a certain new, original, and ornamental Design for Glass Bowls, of which the following is a specification, reference being had to the accompanying drawing, forming a part thereof.

The figure on the drawing is a perspective view of a glass bowl showing my new design.

I claim:

The ornamental design for a glass bowl, as shown.

RICHARD MURR.

Witnesses:

FREDERICK C. GOODWIN,
WALTER M. FULLER.
